UNITED STATES PATENT OFFICE.

FREDRICK A. THURSTON, OF LYNN, MASSACHUSETTS.

INTERNAL-COMBUSTION ENGINE.

1,042,503.

Specification of Letters Patent. Patented Oct. 29, 1912.

Application filed September 29, 1908. Serial No. 455,354.

To all whom it may concern:

Be it known that I, FREDRICK A. THURSTON, of Lynn, in the county of Essex and State of Massachusetts, have invented certain new and useful Improvements in Internal-Combustion Engines, of which the following is a specification.

This invention relates to engines of the type in which a combustible mixture is exploded in the cylinder to drive the piston thereof, and has particular reference to engines of that character which operate with a two-stroke cycle.

The object of the invention is to obviate danger of back-firing into the carbureter and to eliminate the necessity of a check valve in the pipe through which the combustible mixture is admitted to the engine. I accomplish these objects by constructing the engine with its ports so arranged that the piston covers and uncovers them successively at the proper times to insure operation of the engine, and so that the port by which the combustible mixture is first admitted to the engine is covered whenever an explosion takes place. By this means the piston takes the place of valves and renders the same in any of the ports unnecessary. Prevention of back-firing in the carbureter and the pipe leading therefrom to the engine is permitted by having the exhaust port at the most remote possible point from the admission port and by providing that the port through which the fresh mixture is admitted to the engine be closed whenever the exhaust port and the passage through which the mixture is conducted to the combustion chamber are opened. I am enabled to have the exhaust port situated on the opposite side of the engine from the admission port and the passage which conducts the mixture into the combustion chamber, which is the point of maximum remoteness, by the construction which constitutes the present invention, and which is hereinafter described and claimed.

Of the accompanying drawings,—Figure 1 represents an internal combustion engine embodying my invention. Fig. 2 represents an axial section on line 2—2 of Fig. 1. Fig. 3 represents a cross-section on line 3—3 of Fig. 1. Fig. 4 represents a cross-section on line 4—4 of Fig. 1. Fig. 5 represents a cross-section on line 5—5 of Fig. 1.

The same reference characters indicate the same parts in all the figures.

Referring to the drawings, which illus-

trate an internal combustion engine working on the two-stroke cycle, 1 represents the cylinder of the engine, and 2 represents the crank case. This crank case is formed of two parts, one of which is integral with the cylinder casting, and the other of which is bolted to the first part by bolts 3 having flanges 4 for that purpose. 5 represents the piston, 6 the connecting rod, 7 the crank, 8 the shaft, and 9 the fly wheel of the engine.

The crank case and cylinder casting together inclose a space which is air-tight so that it may contain combustible vapor under pressure without danger of leakage. This space is divided by the piston into two chambers of variable volume, one of which is the combustion chamber 10 in the head portion of the cylinder, and the other is a receiving chamber 11 in the crank case and crank end of the cylinder. The combustible mixture of volatile hydrocarbon and air is carried to the engine from a carbureter (not shown) through a pipe 12, and is admitted into the receiving chamber through a port 13 in the wall of the cylinder, which I term the "admission port". This port is opened when the piston is at the head end of its stroke, as illustrated in Fig. 2, and is covered by the piston at all other times. During the working stroke of the engine the volume of combustible mixture in the receiving chamber is compressed, and at the end of this stroke is allowed to flow into the combustion chamber through an inlet port 14, which is connected with the admission chamber by passages hereinafter described. The inlet port 14 is located at such a point in the cylinder wall that it is uncovered by travel past it of the piston when the latter reaches the crank end of its stroke, that is, the end of its working stroke, and is covered by the piston at all other times. The exhausted gases are allowed to escape through an exhaust port 15 and a pipe 16 in the cylinder wall. This port is located nearer the head of the cylinder than is the inlet port 14 so as to be uncovered by the piston and opened to permit the hot burnt gases to escape before the inlet port is opened to the admission of the fresh mixture.

The passage or passages by which the combustible mixture is conducted from the receiving chamber to the inlet port 14 is a divided or two-branch passage which entirely surrounds the inlet port 13. This passage opens into the combustion chamber

at 17 where the cylinder and crank case join, and extends upward. At 18 the passage divides into two branches 19 and 20 which diverge until they are separated more 5 widely than the width of port 13, then extend toward the head of the cylinder in parallel and join together again in the port 14. These branches and the inlet 17 of the 10 passage are contained wholly within the shell or wall of the cylinder, which is made thick enough to provide space for the usual cooling water jacket.

As the openings 21 and 22 into the 15 branches 19 and 20 of the passage constitute ports, it will be seen that this engine contains five ports, these being respectively, the admission port 13, the passage ports 21 and 22, the inlet port 14, and the exhaust port 15. The latter port is on the opposite side 20 of the cylinder from the first four ports, and thus is as far away from them as it can possibly be located. Thereby the danger of fire being communicated to the admission port 13 is reduced to the minimum, for 25 before the piston ceases its travel, the exhaust port is opened and the burning gases can only reach the admission port by traveling between the piston and cylinder walls, and it would have the maximum distance to 30 travel so that danger of this result taking place is made as slight as possible. Also, since the admission port is so remote from the exhaust port and the direct passage from one to the other is closed by the piston, the 35 necessity of having a check valve in the admission pipe 12 is eliminated. Consequently the engine may be operated wholly without valves.

The port 14 is shown as extending entirely 40 through the shell of the cylinder. This construction is adopted for structural reasons wholly, in order to simplify the casting of the engine. As far as concerns the operation of the engine, the port 14 on its outer 45 side might terminate on the same line with the outer boundaries of the passages 19^a and 20^a which lead from the passages 19 and 20 to the port 14. By reason of having the passage from the receiving chamber 50 to the inlet port divided and carried around both sides of the admission port, it is possible to arrange all these ports on the same side of the engine, and at the same time to provide the area requisite to allow the necessary 55 flow of vapor into the combustion chamber, without interfering with any of the appendages of the engine.

I claim:

1. A two-stroke cycle engine comprising a

single cylinder, a crank case connected to 60 the cylinder and a piston reciprocating in such cylinder separating the interior thereof into a combustion chamber and a receiving chamber, the cylinder having in one of its side walls an exhaust port arranged to be 65 opened when the piston is at the crank end of its stroke, an inlet port arranged to be opened when the piston is at the head end of the stroke, and a transfer passage cast in the wall of the cylinder wholly in the opposite side from the exhaust port, communicating with the crank case in a single opening, branching so as to pass around the inlet port and opening into a port in the cylinder wall which is uncovered so as to communicate with the combustion chamber 70 when the piston is at the crank end of its stroke.

2. A two-cycle internal combustion engine 80 comprising a single cylinder and a piston arranged to reciprocate therein and to divide its interior into a combustion chamber and a receiving chamber; the cylinder being formed with an exhaust port in one side wall, with two admission ports in the opposite side wall, one of which admission ports is below the other and is arranged to admit a combustible mixture to the receiving chamber when the piston is at the head end of the stroke, and with a divided passage 85 formed wholly in the cylinder wall at the side opposite to the exhaust port, surrounding the lower admission port and opening into the outer admission port and into the receiving chamber.

3. A two-cycle internal combustion engine comprising a single cylinder having a combustion chamber, a receiving chamber, and a piston separating said chambers from each other, and having an admission port opening into the receiving chamber, a transfer port opening from the receiving chamber and dividing into two branches contained wholly within the cylinder wall at one side of an axial plane and inclosing the admission port between them, a second admission port with which said branches join and so arranged in the cylinder wall as to be uncovered when the piston is at the end of its working stroke, and an exhaust port in the 100 cylinder walls diametrically opposite to the admission ports.

In testimony whereof I have affixed my signature, in presence of two witnesses.

FREDRICK A. THURSTON.
